UNITED STATES PATENT OFFICE.

JOHANNES RUTHS, OF DJURSHOLM, SWEDEN, ASSIGNOR TO RUTHS ACCUMULATOR AKTIEBOLAG, OF STOCKHOLM, SWEDEN.

METHOD OF AND APPARATUS FOR BLEACHING PAPER PULP.

Application filed October 20, 1921, Serial No. 509,134, and in Sweden January 9, 1920.

In such manufacturing processes where it is required to heat a large quantity of a liquid to a certain temperature, and where the heating is effected by means of steam, one has heretofore been compelled to use a relatively long time for this, owing to the fact that it has been impossible to obtain in a short time the quantity of steam required for the purpose from the boiler battery.

Again, if the boiler battery were enlarged so that the process could be finished in a short time, the efficiency of the boiler plant would be considerably lowered in cases where the processes in question are rather intermittent, as there would then during long periods, be only a very slight load on the boilers.

Taking as an example the bleaching process in a sulphite factory, this process generally is performed as follows:

After the bleaching hollander has been filled with pulp and bleaching liquor, the temperature of the liquor is to be raised to about 40 degrees centigrade. This heating is generally effected by leading steam directly into the bleaching liquor, which in the case of a bleaching hollander containing about 70 cubic meters requires a time of from 2 to 3 hours.

The present invention has for its purpose to considerably reduce this period, whereby the time of the whole cycle of operations is also shortened which in turn brings about a corresponding increase in the yield of the plant, besides which the losses due to radiation and cooling are decreased.

This is effected by drawing off the quantity of steam required for the process in a uniform current, which is led into a heat or steam storer having a steam space and a water space, the steam being accumulated in the said storer. From this steam storer steam is then drawn off directly to the bleaching hollander. The quantity of steam is now only limited by the discharging capacity of the storer, and as the same is very great, the time of heating up the liquid can be considerably decreased. Thus it is possible to shorten the heating period from 2 to 3 hours to 20 to 30 minutes. Moreover, this reduction of time may take place without imposing any further load-stresses on the boilers which are entirely relieved of all the peak loads that are apt to occur already in a heating period of 2 to 3 hours.

In fact, according to the present invention, the steam supply from the steam boilers for the bleaching process will be entirely uniform and constant during the whole time of the cycle of operations. If, before the steam flows into the storer, the same is caused to pass through a back pressure turbine, or any other steam consumer, it will also be possible to obtain power from all this steam. Heretofore, this has not been possible. If namely the heating has to take place in a reasonably short time, the engine in question cannot be constructed to any economical advantage to receive large quantities of steam at times, and then to run interveningly under a comparatively slight load. Moreover, there is not always a demand for the power which is generated periodically in the manner described. With the arrangement as suggested in this application the supply of steam to the steam motor may, on the other hand, be about constant, thus causing the power generated also to be constant, such a constant power being always utilizable.

In the accompanying drawings forming part of this specification, Fig. 1 shows diagrammatically an arrangement for carrying my invention into effect. Fig. 2 shows a slightly different arrangement in which a motor such as a back pressure or an extraction turbine is positioned to receive the steam from the boilers before passing to the steam storer.

P denotes the boiler battery, A is the storer, L_1 a piping leading from the boiler battery into the water space of the storer, the said piping delivering steam into the storer A. V is a valve inserted in the piping L_1 , the said valve serving as a means of adjustment for admitting just the desired quantity of steam. B designates a vessel containing the liquid to be heated, in the present case a bleaching hollander. L_2 is a piping leading from the steam space of the storer, and serving as a conduit for steam drawn off from the storer and supplied to the bleaching hollander. V_1 is a valve inserted in the said piping.

In the embodiment shown in Fig. 2, an engine is employed to recover power from the steam, before the latter is fed into the storer. In this figure, T designates the engine inserted into the steam conduit L_1 .

As it often takes a certain time to fill up the hollander, the time of the cycle of operations

may often be reduced still more by using the time of filling the receptacle to simultaneously heat the water. The steam used for the heating may then preferably be employed also for introducing the water or bleaching-liquor into the bleaching hollander by means of an injector or the like inserted in the steam piping.

What I claim as new and desire to secure by Letters Patent of the United States is:—

- 10 1. A method of short time bleaching of paper pulp which comprises generating steam in uniform quantity, accumulating the steam in a suitable storer and quickly supplying substantially the entire volume of stored steam to a bleaching hollander containing pulp.
- 15 2. A method of short time bleaching of paper pulp which comprises generating steam at a uniform rate, leading steam to a suitable storer, accumulating steam in said storer, and simultaneously injecting bleaching liquor into a hollander and heating the liquor by quickly supplying substantially the entire volume of stored steam from the storer.

3. Bleaching apparatus comprising, in combination, a bleaching hollander, a steam storers, a steam boiler, a conduit for conducting steam from said boiler to said storers, a valve in said conduit to control flow of steam therethrough, an injector for quickly discharging the steam from the storers, a second conduit for conducting steam from said storers to said injector, means to supply liquid to said injector, a third conduit for conducting liquid from said injector into said hollander, and a valve for controlling the supply of steam to the injector.

4. A method of short time bleaching of paper pulp which comprises generating a large quantity of steam, accumulating the generated steam in a suitable storers, and quickly supplying therefrom the great quantities of steam necessary for the bleaching process to a bleaching hollander containing pulp.

In testimony whereof I affix my signature.

JOHANNES RUTHS.
